PROCESS FOR THE MANUFACTURE OF
HALOGENATED ALCOHOLS

Hans Meerwein, Marburg, and Erich Goth, Wuppertal-Elberfeld, Germany, assignors to Winthrop Chemical Company, Inc., New York, N. Y., a corporation of New York

No Drawing. Application November 24, 1931,
Serial No. 577,150, and in Germany November
29, 1930

35 Claims. (Cl. 260—156)

The present invention relates to a process of preparing halogenated alcohols from halogenated aldehydes, said process being an improvement in or further development of the processes of U. S. Patents 1,572,742 and 1,725,054.

It is a known fact in the art of reducing halogenated aldehydes to the corresponding alcohols that the halogenated aldehydes occupy an exceptional position with regard to other aldehydes, inasmuch as the alcoholates of magnesium which are known to reduce the non-halogenated aldehydes to the corresponding alcohols without difficulty, fail completely in the case of the halogenated aldehydes. As we have established by experiments, likewise the alcoholates of all metals of the first and second group of the periodic system do not operate when trying to reduce halogenated aldehydes by means of the said metal alcoholates. Up to date only aluminium alcoholates have proved as suitable metal alcoholates for the reduction of the halogenated aldehydes to the corresponding halogen alcohols (compare U. S. Patents 1,572,742 and 1,725,054). This reaction is carried out in the presence of a primary or secondary alcohol.

In accordance with the present invention the reduction of halogenated aldehydes to the corresponding halogenated alcohols is effected by treating the halogenated aldehydes in the presence of a non-tertiary alcohol with an alcoholate of a metal other than aluminium and the metals of the first and second group of the periodic system. Owing to the fact that up to date only aluminium alcoholates could be used for the reduction of halogenated aldehydes, but not, for example, magnesium alcoholate which is capable of transforming only non-halogenated aldehydes into the corresponding alcohols, it is surprising that also alcoholates of metals other than aluminium and those of the first and second group of the periodic system may be employed in the process of preparing halogenated alcohols from the corresponding aldehydes. Apparently the metal alcoholates effect the reduction process by a catalytic action since, in general, it is not necessary to introduce equivalent quantities of the metal alcoholates into the reaction. The process proceeds according to the following reaction scheme:

(R being a halogenated organic, for example, a halogen alkyl, halogen aryl or halogenated arylalkyl radical).

The hydrogen involved in this reaction is sup-

plied by the non-tertiary alcohol present as solvent or also by the alcohol radical present in the metal alcoholate, the alcohols transforming for their part into the corresponding aldehydes.

When performing our new process we prefer to use the metal alcoholates of the metals of the fourth group of the periodic system and of the iron group, especially the alcoholates of zirconium, titanium, tin and iron. Other metals which are, however, not of such great practical interest are, for instance, boron, thallium, lead, manganese, cobalt and nickel. The metal alcoholates are obtainable by reacting upon the metalhalogenides with the alkali metal alcoholates, for example, according to the following equation:

"me" indicating a metal, *n* indicating the valency of the metal. As equivalents halogen metal alcoholates obtainable, for example, according to the following equation:

(*n* having the above meaning, *x* being a number smaller than *n*), may be employed instead of the pure metal alcoholates. Such halogen metal alcoholates, obviously, may also be produced by reacting with hydrohalic acids upon the metal alcoholates. As already indicated above, in general smaller quantities of the metal alcoholates than those which correspond to equivalent amounts, may be employed. For instance, in some cases already the sixth part of the equivalent quantity proves operable.

As non-tertiary alcohols being present as solvent we use preferably secondary alcohols, such as isopropyl alcohol, isobutyl alcohol and cyclohexanol, but also primary alcohols, especially ethyl- and propyl-alcohol, further, for example, benzyl alcohol have proved operable. When using a sufficient quantity of the metal alcoholate, it is not necessary that larger quantities of a free non-tertiary alcohol are present in the reduction mixture. The metal alcoholates and the non-tertiary alcohols may each be employed also in admixture with one another.

The non-tertiary alcohol to be used as a solvent or reducing agent in the reaction mixture is advantageously chosen dependent on the boiling points of the halogenated aldehyde to be reduced and of the halogen alcohol formed, since it has proved advisable to distil off during the reaction the aldehyde or the ketone formed from

the non-tertiary alcohol having the lowest boiling point. Accordingly the reaction temperature is dependent on the boiling point of the non-tertiary alcohol being present as solvent or reducing agent, and is preferably between 70 and 120° C. When using a relatively small quantity of the non-tertiary alcohol the temperature may be relatively high in comparison with the boiling point of the non-tertiary alcohol, since, of course, 10 the mixture in such case has a higher boiling point. When using non-tertiary alcohols of a higher boiling point it is often advantageous to hold the reaction temperature lower than the boiling point. The reaction time is dependent on 15 the temperature used and may vary within wide limits, for example, from 2 to 24 hours.

As halogenated aldehydes saturated and unsaturated aliphatic, aromatic and aliphatic-aromatic halogen aldehydes come into consideration. 20 The new process preferably is intended to be used for the production of halogenated alkyl aldehydes from the corresponding halogenated alkyl aldehydes, such as halogenated acetaldehydes, for example, tribromo- and trichloroacetaldehyde, 25 furthermore, alpha-, alpha-, beta-trichloro butyraldehyde, alpha- chloro- and alpha-bromo-crotonaldehyde. Suitable halogenated aromatic aldehydes are, for example, halogen-benzaldehydes, halogen cinnamic aldehyde and 30 the like.

Our new process is advantageously performed in the following manner: the solution of the metal alcoholate in the non-tertiary alcohol as obtained by the action of an alkali alcoholate 35 solution upon the metal halogenide is mixed with the halogenated aldehyde and, while heating and passing through an indifferent gas, the solvent is distilled off; always the quantities of the non-tertiary alcohol distilled off are replaced 40 by the non-tertiary alcohol. With the solvent distilling off simultaneously the dehydrogenated alcohol, being an aldehyde or ketone, is removed from the reaction mixture as quantitatively as possible; then the mixture is acidified and the 45 halogen aldehyde, produced in general in a good yield, may be separated by steam distillation or by extraction with an organic solvent.

The invention is illustrated by the following examples without being restricted thereto:

50 Example 1

13.1 grams of zirconium tetrachloride are dissolved in 76.2 grams of absolute isopropyl alcohol. This solution is dropped slowly into a boiling 55 sodium isopropylate solution (from 4.76 grams of sodium and 76.2 grams of absolute isopropyl alcohol), whereupon sodium chloride is precipitated in a finely divided form. The milky liquid is maintained at the boiling point for some time 60 longer under a reflux condenser, 140.5 grams of bromal are added and the solvent which must be continually replaced is distilled off while passing through nitrogen. Almost the theoretical quantity of acetone passes over with the solvent. After 65 some 5½ hours the greater part of the solvent remaining is distilled off, dilute sulfuric acid is added and the tribromoethyl alcohol, which is produced in a very good yield, is driven off by means of steam and isolated by known methods.

70 The treatment of the sodium isopropylate solution with the zirconium tetrachloride solution can likewise be carried out at room temperature.

Instead of the zirconium tetra-isopropylate used above the reaction may be performed with 75 a halogen-zirconium-isopropylate, for instance,

with mono-chloro-zirconium-tri isopropylate, being produced by using for the preparation of the sodium isopropylate to be added to the zirconium tetrachloride only 3.57 grams of sodium metal or by adding about 40 grams of a 5% solution of hydrochloric acid in isopropyl alcohol.

Example 2

14.5 grams of stannic tetrachloride are dropped into a sodium isopropylate solution (from 5 85 grams of sodium and 160 grams of absolute isopropyl alcohol). 77 grams of chloral are then added gradually to the boiling solution. The distillation of the solvent, which must be continually replaced, is then begun in a current of an indifferent gas. After some 6 hours the greater part of the solvent remaining is distilled off. Dilute sulfuric acid is then added and the trichloroethyl alcohol, which is produced in a very satisfactory yield, is driven off by means of steam and 90 isolated.

Instead of stannic chloride there can also be added to the sodium isopropylate the equivalent quantity of another appropriate metallic salt, for example, titanium tetrachloride, in order to carry 100 out the reduction by means of titanium isopropylate; or, instead of the above indicated quantity of zirconium tetrachloride a mixture of, for instance, 6.6 grams of zirconium chloride and 7.3 grams of stannic chloride may be used. 105

Example 3

9.1 grams of anhydrous ferric chloride are dissolved in 90 grams of absolute isopropyl alcohol. This solution is run into a boiling sodium isopropylate solution (from 3.7 grams of sodium and 70 grams of absolute isopropyl alcohol). After 110 the addition of 140.5 grams of bromal the distillation of the solvent is begun. After some 6 hours tribromoethyl alcohol is formed in a very 115 satisfactory yield and is isolated as described in Example 1.

Example 4

37.3 grams of tin ethylate are heated to about 80° C. for about 3 hours with 25 grams of absolute ethyl alcohol and 140.5 grams of bromal, advantageously while passing through an indifferent gas. When nearly the theoretical quantity of acetaldehyde has been evolved, dilute sulfuric acid is added and the tribromoethyl alcohol 125 is separated in the manner already described.

Example 5

From 13 grams of zirconium tetrachloride in 76 grams of absolute isopropanol and 4.7 grams 130 of sodium in 76 grams of isopropanol a solution of zirconium isopropylate in isopropanol is prepared in accordance with the directions given in Example 1. 52 grams of alpha-chloro-crotonaldehyde are dropped into this solution and during 135 3 hours a mixture of isopropanol and acetone is distilled off while passing through nitrogen and continually replacing the solvent which distils off. The residue is then treated with dilute sulfuric acid and the alpha-chloro-crotylalcohol, 140 which is produced in a very good yield is isolated by known methods.

By using instead of the above indicated quantity of alpha-chloro-crotonaldehyde 84 grams of alpha-chloro-cinnamic aldehyde and working up 145 in the same manner, alpha-chloro-cinnamic alcohol is obtained.

Example 6

A solution of 16 grams of zirconium tetrachloride in 100 grams of water-free propyl alcohol 150

- is mixed with a solution of a 6.75 grams of sodium in 100 grams of propyl alcohol while hot. After the addition of 140.5 grams of tribromoacetaldehyde, the mixture is heated at 95° C. 5 during 8 hours. Then the propionic aldehyde formed and the main part of the solvent are distilled off, dilute sulfuric acid is added and the tribromoethylalcohol is separated in the above described manner.
10. Instead of propyl alcohol may be employed, for example, a butyl alcohol as solvent or reducing agent.
- We claim:—
1. The process which comprises reacting upon a halogenated aldehyde with an alcoholate selected from the group consisting of metal-alcoholates and halogen-metal alcoholates of monohydric non-tertiary alcohols, with a metal other than aluminium and the metals of the first and second group of the periodic system in the presence of a non-tertiary alcohol.
  2. The process which comprises reacting upon a halogenalkyl aldehyde with an alcoholate selected from the group consisting of metal-alcoholates and halogen-metal-alcoholates of monohydric non-tertiary alcohols with a metal other than aluminium and the metals of the first and second group of the periodic system in the presence of a non-tertiary alcohol.
  3. The process which comprises reacting upon a halogenated acetaldehyde with an alcoholate selected from the group consisting of metal-alcoholates and halogen-metal-alcoholates of monohydric non-tertiary alcohols with a metal other than aluminium and the metals of the first and second group of the periodic system in the presence of a non-tertiary alcohol.
  4. The process which comprises reacting upon tribromoacetaldehyde with an alcoholate selected from the group consisting of metal-alcoholates and halogen-metal-alcoholates of monohydric non-tertiary alcohols with a metal other than aluminium and the metals of the first and second group of the periodic system in the presence of a non-tertiary alcohol.
  5. The process which comprises reacting upon a halogenated aldehyde with an alcoholate selected from the group consisting of metal-alcoholates and halogen-metal-alcoholates of monohydric non-tertiary alcohols with a metal of the fourth group of the periodic system, in the presence of a non-tertiary alcohol.
  6. The process which comprises reacting upon a halogenalkyl aldehyde with an alcoholate selected from the group consisting of metal-alcoholates and halogen-metal-alcoholates of monohydric non-tertiary alcohols with a metal of the fourth group of the periodic system, in the presence of a non-tertiary alcohol.
  7. The process which comprises reacting upon a halogenated acetaldehyde with an alcoholate selected from the group consisting of metal-alcoholates and halogen-metal-alcoholates of monohydric non-tertiary alcohols with a metal of the fourth group of the periodic system, in the presence of a non-tertiary alcohol while heating.
  8. The process which comprises reacting upon tribromoacetaldehyde with an alcoholate selected from the group consisting of metal-alcoholates and halogen-metal-alcoholates of monohydric non-tertiary alcohols with a metal of the fourth group of the periodic system, in the presence of a non-tertiary alcohol while heating.
  9. The process which comprises reacting upon a halogenated aldehyde with an alcoholate select-
- ed from the group consisting of zirconium-alcoholates and halogen-zirconium-alcoholates of a monohydric non-tertiary alcohol in the presence of a non-tertiary alcohol.
10. The process which comprises reacting upon a halogenalkyl aldehyde with an alcoholate selected from the group consisting of zirconium-alcoholates and halogen-zirconium-alcoholates of a monohydric non-tertiary alcohol in the presence of a non-tertiary alcohol.
11. The process which comprises reacting upon a halogenated acetaldehyde with an alcoholate selected from the group consisting of zirconium-alcoholates and halogen-zirconium-alcoholates of a monohydric non-tertiary alcohol in the presence of a non-tertiary alcohol while heating.
12. The process which comprises reacting upon tribromoacetaldehyde with an alcoholate selected from the group consisting of zirconium-alcoholates and halogen-zirconium-alcoholates of a monohydric non-tertiary alcohol in the presence of a non-tertiary alcohol while heating.
13. The process which comprises reacting upon trichloroacetaldehyde with an alcoholate selected from the group consisting of zirconium-alcoholates and halogen-zirconium-alcoholates of a monohydric non-tertiary alcohol in the presence of a non-tertiary alcohol while heating.
14. The process which comprises reacting upon a halogenated aldehyde with an alcoholate selected from the group consisting of zirconium-alcoholates and halogen-zirconium-alcoholates of a monohydric non-tertiary alcohol in the presence of a secondary alcohol.
15. The process which comprises reacting upon a halogenalkyl aldehyde with an alcoholate selected from the group consisting of zirconium-alcoholates and halogen-zirconium-alcoholates of a monohydric non-tertiary alcohol in the presence of a secondary alcohol.
16. The process which comprises reacting upon a halogenated aldehyde with an alcoholate selected from the group consisting of zirconium-alcoholates and halogen-zirconium-alcoholates of a monohydric non-tertiary alcohol in the presence of isopropyl alcohol.
17. The process which comprises reacting upon a halogenalkyl aldehyde with an alcoholate selected from the group consisting of zirconium-alcoholates and halogen-zirconium-alcoholates of a monohydric non-tertiary alcohol in the presence of isopropyl alcohol.
18. The process which comprises reacting upon a halogenated acetaldehyde with an alcoholate selected from the group consisting of zirconium-alcoholates and halogen-zirconium-alcoholates of a monohydric non-tertiary alcohol in the presence of isopropyl alcohol while heating.
19. The process which comprises reacting upon tribromoacetaldehyde with an alcoholate selected from the group consisting of zirconium-alcoholates and halogen-zirconium-alcoholates of a monohydric non-tertiary alcohol in the presence of isopropyl alcohol while heating.
20. The process which comprises reacting upon trichloroacetaldehyde with an alcoholate selected from the group consisting of zirconium-alcoholates and halogen-zirconium-alcoholates of a monohydric non-tertiary alcohol in the presence of isopropyl alcohol while heating.
21. The process which comprises reacting upon a halogenated aldehyde with the isopropylate of zirconium in the presence of isopropyl alcohol.
22. The process which comprises reacting upon

- a halogenalkyl aldehyde with the isopropylate of zirconium in the presence of isopropyl alcohol.
23. The process which comprises reacting upon a halogenated acetaldehyde with the isopropylate of zirconium in the presence of isopropyl alcohol while heating.
24. The process which comprises reacting upon tribromoacetaldehyde with the isopropylate of zirconium in the presence of isopropyl alcohol while heating.
25. The process which comprises reacting upon trichloroacetaldehyde with the isopropylate of zirconium in the presence of isopropyl alcohol while heating.
- 15 26. The process which comprises reacting upon a halogenated aldehyde with an alcoholate selected from the group consisting of metal-alcoholates and halogen-metal-alcoholates of a monohydric non-tertiary alcohol with a metal of the iron group in the presence of a non-tertiary alcohol.
- 25 27. The process which comprises reacting upon a halogen alkylaldehyde with an alcoholate selected from the group consisting of metal-alcoholates and halogen-metal-alcoholates of a monohydric non-tertiary alcohol with a metal of the iron group in the presence of a non-tertiary alcohol.
- 30 28. The process which comprises reacting upon tribromoacetaldehyde with an alcoholate selected from the group consisting of metal-alcoholates and halogen-metal-alcoholates of a monohydric non-tertiary alcohol with a metal of the iron group in the presence of a non-tertiary alcohol while heating.
- 35 29. The process which comprises reacting upon a halogenated aldehyde with an alcoholate selected from the group consisting of iron-alcoholates and halogen-iron-alcoholates of a monohydric non-tertiary alcohol in the presence of a non-tertiary alcohol while heating.
